UNITED STATES PATENT OFFICE

ROLLA W. CALLAWAY AND HARRISON ANDERSON, OF LOS ANGELES, CALIFORNIA;
SAID ANDERSON ASSIGNOR TO SAID CALLAWAY

BOOKHOLDER

Application filed September 19, 1928. Serial No. 307,004.

Our invention has reference to holders for books and the like, by which a book may be supported and held in open position for reading, and it has for a purpose the provision of a book holder which is particularly adapted, although not necessarily, for association with a chair to hold a book in convenient position for reading by the person occupying the chair, our invention being further characterized by its adaptability to the arm of a chair in such manner that when not in use it may be stored within the chair arm and thus completely concealed from view.

It is also a purpose of our invention to provide a book holder which is characterized by its structural simplicity, ease of operation, and adaptability to securely hold a book supported thereon at any level, distance, and angle to suit the particular requirements of a person occupying the chair with which the book holder is associated.

We will describe only one form of book holder embodying our invention and will then point out the novel features in claims.

In the accompanying drawings:

Figure 1 is a view showing in side elevation one form of book holder embodying our invention in stored position within the arm of a chair, the latter being shown in fragmentary section;

Fig. 2 is a view similar to Fig. 1 showing the book holder extended from the chair arm and in book-supporting position;

Fig. 3 is a view similar to Fig. 2 showing another position of adjustment of the book holder;

Fig. 4 is an enlarged vertical sectional view taken on the line 4—4 of Fig. 2 and looking in the direction of the arrows;

Fig. 5 is a further enlarged fragmentary sectional view taken on the line 5—5 of Fig. 4;

Fig. 6 is an enlarged sectional view taken on the line 6—6 of Fig. 4;

Fig. 7 is a horizontal sectional view taken on the line 7—7 of Fig. 4 and showing the book rack in released position for angular adjustment;

Fig. 8 is a fragmentary view showing in side elevation and partly in section a modi-

fied means for securing the post of the book holder in vertically adjusted position;

Fig. 9 is a sectional view taken on the line 9—9 of Fig. 8;

Fig. 10 is a sectional view taken on the line 10—10 of Figure 5; and

Figure 11 is an enlarged sectional view taken on the line 11—11 of Figure 3.

In carrying out our invention, we provide a base frame F comprising upper and lower parts 15 and 16 and an intermediate part 17, the latter connecting the former, and the former being provided with vertically aligned openings 18 in which is slidably received a post P. The vertical portion 17 of the frame F may have screws 19 extended therethrough as shown in Fig. 2 for securing the latter to a support. This support in the present instance comprises the arm and leg portion of a chair, and, as shown in Figs. 1 and 2, such portion is hollow in order that the entire frame may be extended thereinto and secured in proper position to support the post in upright position. The post is circular in cross-section to have free vertical sliding movement within the parts 15 and 16 of the frame, the post in its upward movement being limited by a transverse pin 20 extended through the lower end of the post as shown in Fig. 4. To prevent turning of the post in the frame in any position of its vertical adjustment it is formed with a key 21 co-extensive in length with the post and vertically movable in suitable extensions of the openings 18 and frame.

The post P is capable of being latched in vertically adjusted position by the provision of a pawl 22 pivoted on ears 23 of the upper bracket part 15 and spring-pressed to normally engage the teeth of a rack 24 formed on the post by recessing the latter at intervals as will be understood from a consideration of Fig. 4. The teeth of the rack extend downwardly as shown in Fig. 2 so that when engaged by the pawl 22 the two co-operate in securing the post against downward movement.

As illustrated to advantage in Fig. 5, the upper end of the post P is provided with a reduced extension which forms a stub axle 100

25 upon which a connecting arm 26 is supported and rotatable to occupy any position within a circle. This axle 25 is capable of being latched in any position by means of co-
5 acting latch members 26a and 27 on the axle and arm, respectively. The latching member 26a is in the form of a miter pinion, the teeth of which are adapted to engage the teeth of the member 27 which is in the form
10 of an interrupted miter pinion, preferably cast integral with the arm 26. To disengage the two latch members, the member 26a is mounted for movement upwardly on the axle 25 so that it may be manually lifted to cause
15 its teeth to disengage the teeth of the latch member 27. To confine the latch member 26a against displacement from the axle, a pin 28 extends through a slot 29 in the axle 25, with the pin secured to a collar 30 of the latch member. The pin and slot also co-act to prevent rotation of the latch member on the axle so that when the member is in engagement with the member 27 the arm 26 will be locked against rotation in either direction on the
20 25 axle 25.

The connecting arm 26 is relatively short, but of substantial construction for it is designed to connect the post with a rack arm 31, while the rack arm in turn supports a
30 rack 32 in which latter the book is adapted to be supported. The rack arm 31 is provided with a head 33 rotatable on a stub axle 34 permanently secured within the arm 26 and detachably associated with the head 33
35 by a screw 34a threaded in the lower end of the axle and carrying a flange and washer 35 in order to prevent downward displacement of the head from the axle. By means of this connection the arm 31 is supported for rotation about the axle 34 as a center, and to latch the arm in any adjusted position we provide a pin 36 in the connecting arm 26, and which, as shown in Fig. 5, has a portion extended above the arm which is provided with a handle 37 and another portion extending into a
40 pocket 38 of the arm and provided with a head 39 adapted to engage in any one of a circular series of recesses 40 in the top of the head 33. The pin 36 is yieldably urged downwardly to maintain the head 39 within any one recess by means of a spring 41. Thus, it will be understood that by pulling upwardly on the handle 37, the head 39 can be elevated free of the recesses 40 to permit turning
45 movement of the head 33, and, consequently, the arm 31 on the axle 34. Once the circumferential adjustment of the arm 31 is effected, the pin 36 can be released, thus causing the head 39 to again engage within a recess 40 to lock the arm in this adjusted position.

The book rack 32 is in the form of a rectangular plate of metal or other suitable material having an L-shaped lip 42 at the lower edge therebetween upon which the lower edge of
50 55 60 the book is adapted to rest. At the rear side

of the rack spaced flanges 43 are provided, formed with openings through which the rack arm 31 is extended in such manner that the arm provides a support upon which the rack can be rotated to occupy different angular positions and to thereby support a book at any required angle to facilitate reading. To latch the rack in any angular position of adjustment, we provide latch elements on the rack and arm normally engaging each other but adapted to be moved to released position in order to permit the rack to be manually moved to any desired angle. The arm 31 is provided with two latch elements 44 in the form of miter pinions fixed to the arm by pins 45. Interposed miter pinions 46 form the latch elements on the rack 32, and these elements are welded or otherwise secured to the rack 32 in such positions that they coact with the elements 44 to secure the rack against rotation on the arm.

The rack 32 is urged to the right as when viewed in Fig. 4, so that the latch elements 46 normally engage the latch elements 44. For this purpose we provide a spring 47 interposed between one of the flanges 43 and a collar 48 at one side of a pin 49 extended through the arm 31. This spring 47 is of such tension as to permit the rack 32 to be moved to the left from the position shown in Fig. 4 to that shown in Fig. 7, in which the elements 46 are moved free of the elements 44. With the rack in this position it will be evident that it can be manually rotated on the arm 31 to assume any angular position desired. Once the rack is released the spring 47 functions to return it to the normal position shown in Fig. 4 where the latch elements again function to secure the rack against movement.

From the foregoing construction taken in conjunction with the accompanying drawings, it will be manifest that we have provided a book holder in which the post P allows of a vertical adjustment of the arm 31 and the rack 32 in order that the rack may occupy any desired elevation. The arm 31 being rotatable on the post P can be moved to any desired position in order that the rack may be positioned in any desired horizontal relation with respect to the reader. By an adjustment of the rack 32 on the arm 31, it can be moved to any desired angle so as to support a book at a corresponding angle to suit the particular requirements of a reader.

In the adaptation of our invention to a chair, as illustrated in Figs. 1, 2, and 3, one leg and arm may be made hollow in order to provide a compartment K in which the book holder is adapted to be received. This compartment is normally closed by a lid L, and when the lid is open access may be had to the book holder for extending the post P therefrom to allow the subsequent adjustment of the arms 26 and 31, and, if necessary, the adjustment

of the rack 32 all to the end of adjusting the rack in such manner that a book placed thereon can be positioned and supported at the place and angle most convenient for reading by the occupant of the chair. It is important to note that the connecting arm 26, being horizontally movable on the axle 25, can be adjusted from the extreme position shown in Fig. 2 to that shown in Fig. 3, and to any intermediate position, all for the purpose of advancing the arm 31 to position the rack 32 in more advance position with respect to the chair so that the book may be supported at a greater distance from the reader than is possible without adjustment of the arm 26. Other important features of our invention are the latching members 26a and 27, the mounting of the latching member 26a permitting a quick release of the connecting arm 26 to allow rapid circumferential adjustment thereof, and a correspondingly quick engagement with the member 27 to secure the arm 26 in adjusted position. Another important feature is the spring-pressed 25 latch pin 36 engaging within the notches or recesses 40 of the head 33. This construction provides a quick release to permit adjustment of the rack arm 31, and a correspondingly quick engagement to secure the arm in adjusted position.

Our invention also embodies a holder H associated with the rack 32 to retain the leaves of an open book supported on the rack against turning. This holder in the present instance comprises a single length of wire bent to provide a U-shaped portion 50 having terminal extensions 51 disposed laterally and journaled in suitable bearings 52, the latter being secured to the rear side of the rack 32. Knurled handles 53 are provided on the ends of the extensions so as to extend beyond the ends of the rack and either handle may be gripped for rotating the leaf holder to disengage the leaves of the book in order to permit turning of the leaves. As shown in Figs. 2 and 3, the intermediate portion 50 is curved upwardly so as to extend around the lower edge of the rack and to engage the leaves of the book on the rack. The leaf holder is held in this position by any suitable means such as the rubber sleeve 54 loosely embracing one of the extensions 51 and urged into frictional engagement therewith by means of a spring 55, all as clearly illustrated in Figs. 4 and 6. It will be understood that the spring holds the sleeve against rotation on the extension 51 and urges the sleeve against the extension with a force sufficient to set up a friction which will yieldably retain the leaf holder against rotation.

In Fig. 8, we have shown another means for securing the post P in vertically adjusted position within the frame F in substitution for the rack 24 and the jawl 22. This means 65 comprises a block 56 slidable horizontally be-

tween the frame parts 15 and 16 and urged into engagement with the post P by springs 57 mounted on pins 58. The block 56 may be formed of wood or any other suitable material which, when pressed against the post P by the springs 57, will function to frictionally retain the post against vertical sliding movement within the frame. The friction thus set up is insufficient to hold the post against vertical movement when endwise force is applied to the post so that manual adjustment of the post may be effected.

Although we have herein shown and described only one form of book holder embodying our invention, it is to be understood that various changes and modifications may be made herein without departing from the spirit of the invention and the spirit and scope of the appended claims.

We claim:

1. A post, means for supporting the post for vertical adjustment, a splined connection between the post and first means for securing the post against rotation in any position of adjustment, a connecting arm rotatable on the post, means for latching the connecting arm in adjusted position circumferentially on the post, a rack arm rotatable on the connecting arm, latching means for securing the rack arm in adjusted position circumferentially on the connecting arm, and a book rack carried by the rack arm.

2. A book holder comprising a frame, a post movable vertically in the frame, a key on the post engaging the frame to secure the post against rotation in the frame, a rack on the post, a spring-pressed pawl engaging the rack for securing the post in vertically adjusted position within the frame, a stub axle on the upper end of the post having a slot therein, a connecting arm rotatable on the axle, a latching member on the connecting arm, a second latching member on the axle, a pin extending through the second latching member and said slot for securing the latching member against rotation on the axle, the second latching member loosely embracing the axle to permit elevation thereof to disengage the first latching member, said latching members normally coacting to secure the connecting arm in adjusted position circumferentially on the axle, a second stub axle secured in the connecting arm and depending therefrom, a rack arm having a head rotatable on the second stub axle, a spring-pressed latch pin engaging the head to secure the rack arm in any adjusted position circumferentially on the stub axle, a book rack having flanges on the rear side thereof receiving the rack arm whereby the book rack is rotatable on the rack arm to occupy various angular positions and movable longitudinally on the arm to occupy either of two extreme positions, coacting latching elements on the rack arm and rack for securing the rack in

115

120

125

130

any angular position on the arm when in one of said extreme positions, and means for yieldably urging the rack to the last-mentioned extreme position.

3. In a book holder, a post, an arm rotatable on the post and provided with teeth, a toothed element movable vertically on the post above the arm so as to normally engage the teeth of said arm and latch the arm in any adjusted position circumferentially of the post, said element being capable of elevation on the post to disengage said teeth and thus permit adjustment of the arm.
